UNITED STATES PATENT OFFICE.

MAURICE B. NATHANSON, OF LEOMINSTER, MASSACHUSETTS.

PUFF-FORMING BARRETTE.

956,991.

Specification of Letters Patent.

Patented May 3, 1910.

Application filed May 28, 1909. Serial No. 498,959.

To all whom it may concern:

Be it known that I, MAURICE B. NATHANSON, citizen of the United States of America, residing at Leominster, in the county of 5 Worcester and State of Massachusetts, have invented certain new and useful Improvements in Puff-Forming Barrettes, of which the following is a specification.

This invention relates to toilet articles 10 and particularly to barrettes.

An object of this invention is to produce a puff or roll forming barrette which will press the hair into shape to simulate an ordinary puff, the said barrette being capable 15 of construction to form one or a plurality of puffs according to the number of sections comprising the body of the barrette.

A further object of this invention is to provide a body and a tongue coating 20 therewith for pressing hair through openings which are formed in the body, the said openings being, under ordinary conditions, filled with hair that is clamped between the tongue and the body.

25 A further object of this invention is to produce a barrette which, in its construction, may comprise metal, shell, horn, or celluloid, viscoloid, or other composition, in which the body is ornamented in any 30 appropriate way, the said body preferably being provided with a coating member which is carried by the body, although it has been found in practice that the body may be secured in place by long pins or so 35 called hair pins.

With the foregoing and other objects in view, the invention consists in the details 40 of construction and in the arrangement and combination of parts to be hereinafter more fully set forth and claimed.

In describing the invention in detail, reference will be had to the accompanying drawings forming part of this specification wherein like characters denote corresponding 45 parts in the several views, in which—

Figure 1, illustrates a barrette embodying the invention by a view in elevation; Fig. 2, illustrates a longitudinal sectional view taken to one side of the pivotal support for 50 the barrette retaining device; Fig. 3, illustrates a transverse sectional view; and Fig. 4, illustrates a view in elevation of the rear of a barrette showing a slightly modified construction.

55 In these drawings 5, denotes a body which is a frame-like structure having a series of

openings 6, 6, 6, although of course, the body may be formed having one or a plurality of frames with openings and I do not, therefore, wish to be limited with respect to the 60 number or the configuration of the so called frames forming the sections of the body. At each end of the body, I provide perforations 7, which are primarily for the purpose of ornamenting the said body, although 65 these openings may be utilized for the insertion of securing devices such as hat pins, hair pins, or the like in the event of fracture of the body retaining device or where the body retaining device is omitted in the man- 70 ufacture.

The rear surface of the body is provided with two ears 8, having the pivotal pin 9, therein on which the tongue 10, is swingingly mounted. The tongue 10, is bent to 75 form a series of shoulders 11, which correspond in number to the openings 6, in the body, and the said shoulders project into the openings as fully shown in Fig. 2. The end of the body opposite the ears 8, is provided with a hook or tongue engaging member 12, the construction of which may be variously modified to suit particular requirements, but as shown in Fig. 2, the retaining device 12, is in the shape of curved lugs 80 extending from the rear surface of the body. The member 12, serves, in the instance shown in Fig. 2, to engage the end of the tongue and this construction is the ordinary one for 85 hair ornaments. 90

As shown in Fig. 3, the hair illustrated by the numeral 13, is being pressed through one of the openings of the body by the tongue 10, and the hair that is exposed through the opening is in the general contour of a puff. 95 It will be seen from an inspection of this illustration that the effect of a puff may be attained with a comparatively small amount of hair so that with the employment of this barrette, an effective arrangement of the 100 hair may result and in case the hair is fluffy the result will be more effective.

In the modification shown in Fig. 4, the body 14, is practically of the same construction as that heretofore described and the 105 said body is provided with ears 15, to form a pivotal support for the tongue 16, which tongue is double and has shoulders similar to those heretofore described which are designed to enter openings in the body. In 110 fact, the construction shown in Fig. 4, is the same as that heretofore described with the

exception that in Fig. 4, I show the two tongues which merge at the end where the tongue is pivoted to the ears 15. The retaining device 16, in Fig. 4, is of the same construction as that described in connection with the disclosure of the invention shown in Figs. 1, 2, and 3.

I claim—

In a barrette, a body having hair receiving openings therein and a tongue having a

series of shoulders projecting into the said openings for pressing hair through the openings to form puffs, and means for holding the tongue in its adjusted position.

In testimony whereof, I affix my signature 15 in the presence of two witnesses.

MAURICE B. NATHANSON.
